17 Claims. (Cl. 210—51)

1

This invention relates to improvements in centrifugal separators, and more especially concerns a novel continuous centrifuge for the separation of solids from liquids such as fiber from pineapple juice or the like.

An important object of the present invention is to provide a simple, compact and highly efficient continuous centrifugal separator for the separation of solids on the order of pulp and fiber entrained in fruit juices to be clarified, such as pineapple juice and the like.

Another object of the invention is to provide a continuous centrifugal separator in which the removal of solids from a liquid is effected in an unusually smooth and uniform manner which minimizes agitation that might cause foaming or frothing.

A further object of the invention is to provide a continuous centrifuge for removing solids from a liquid and having improved means for separating entrained air from the liquid as a continuous part of the separating action of the apparatus.

Still another object of the invention is to provide a separator of the character indicated in which improved results are attained through the action of a novel rotor and impeller structure.

A still further object of the invention is to provide a novel relationship of a solids collector and centrifugal impeller.

Other objects, features and advantages of the present invention will be readily apparent from the accompanying detailed description of certain preferred embodiments thereof taken in conjunction with the accompanying three sheets of drawings, in which:

Figure 1 is an elevational view of a continuous centrifuge embodying the features of the invention, and showing certain associated equipment more or less schematically;

Figure 2 is a diametrical vertical sectional view taken substantially along the line II—II of Figure 1;

Figure 3 is a horizontal sectional view taken substantially along the line III—III of Figure 2;

Figure 4 is a horizontal sectional view taken along substantially the line IV—IV of Figure 2; and

Figure 5 is a fragmentary sectional view taken in substantially the same plane as Figure 2 but showing a modified form of the invention providing for separation of air from the liquid undergoing centrifugal treatment.

Having more particular reference to the drawings, a centrifuge 10 (Figs. 1 and 2) embodying

2

the features of the invention, is adapted to be carried by a mounting plate 11 supported by a frame 11a at a suitable height above a floor or base. Supported by the mounting plate 11 and projecting through an opening 12 in the plate is an elongated bearing housing 13 for a centrifuge drive shaft 14. Any suitable source of power, such as an electric motor 15, may be provided for driving the shaft 14 and for this purpose may be equipped with a drive pulley 17 connected by drive belts 18 with a pulley 19 fixed upon the drive shaft.

A liquid to be clarified, such as pineapple juice or the like, is adapted to be supplied to the centrifuge 10 from any suitable source of supply such as an extractor (not shown) through an intake 20 which may be connected by suitable conduit with the source of supply. The intake 20 is preferably mounted to communicate axially with the bottom of the centrifuge 10.

Separated liquid is discharged through a radially opening port 21 which is adapted to be placed in communication by way of suitable conduits with a storage receptacle or bottle-or-can filling hopper or the like. Separated solids are ejected from the centrifuge as a continuous process through one or more discharge ports 22 leading to respective control valves 23 which are adjusted to maintain a predetermined back pressure on the ejected solids.

Upon entering the centrifuge 10 through the inlet 20, the liquid carrying entrained solids is fed, preferably under low pressure, through an axial passage 24 to a distribution chamber 25 which is defined by a concentric circular well in the opposing face of a shrouded type rotor-impeller 28 of generally flattened form carried by the lower end of the drive shaft 14. From the distribution chamber 25, the liquid with entrained solids is drawn and impelled by centrifugal action in the rotation of the rotor 28 radially outwardly through expanding volute passages 29 (Fig. 3) to the periphery of the rotor where the solids are driven into spirally enlarging collector channels 30 respectively leading to the discharge ports 22 in the wall of a collector ring 31 surrounding the rotor 28 peripherally. The separated liquid or filtrate is driven by impeller vane extensions 32 on the rotor periphery in reverse direction radially inwardly through diminishing or progressively contracting volute collection or skimmer passages 33 (Fig. 4) communicating with an annular gravity passage 34 from which the descending

liquid flows into a collector head chamber 35 and then out through the discharge port 21.

All of the various fluid chambers and passages in the centrifuge, are provided by a few relatively simple concentrically interfitting parts which can be very economically formed as castings adapted to be conveniently machined for snug internested fit in the assembly. In addition to the collector ring 31, the assembly includes a head plate member 37 which is formed with a rabbet groove 38 on its lower outer margin providing a complementary seat for nested registration therewith of the collector ring 31. On its upper face, the head member 37 is formed with an upstanding radially inwardly facing annular shoulder 39 defining a seating area 40 for receiving a centering lateral annular flange 41 on the lower end of the bearing housing 13 and lying against the margin of the base plate 11 about the clearance aperture 12. A plurality of screws 42 secure the head member 37 and the supporting flange 41 fixedly together and to the base plate 11. At the center of the head member 37 is a bore 43 clearing a hub 44 projecting from the top of the rotor 28.

Seated against the collector ring 31 is a skimmer plate 45 which is formed with a marginal rabbet groove 46 complementary to the opposed surfaces of the collector ring 31 for centered internested assembly therewith. A plurality of bolts 47 secure the collector ring 31, the top member 37 and the skimmer plate 45 securely, but detachably together.

It is within the skimmer 45 that the diminishing spiral fluid passages 33 are provided, such passages being defined by spiral vanes in the form of integral partitions 48, the direction of spiral being generally in the direction of rotation of the rotor 28. The annular gravity fluid passage 34 is provided in part by an annular groove 49 in the skimmer plate 45 communicating freely with the inner end of the skimmer passages 33.

Substantially completing the external assembly of the centrifuge is a bottom member 50 which internestingly interengages with the skimmer plate 45 and has an annular gravity fluid passage groove 51 registering with the complementary passage groove 49 and completing the liquid gravity fluid passageway 34, the collecting chamber 35 being cored out below the groove 51. A centered relationship of the bottom member 50 with the skimmer plate 45 is attained by the reception of a reduced diameter axial stem portion 52 extending from the bottom member into a complementary axial bore 53 in the skimmer plate 45.

To secure the bottom member 50 to the skimmer plate 45 in any preferred rotary adjusted position particularly for angular adjustment of the outlet 21 L-clamps 54 are secured by stud bolts 55 against a clamping shoulder 57 provided by a flange projecting laterally from the bottom member against the skimmer plate.

It will be observed from Fig. 2 that the bottom member stem 52 cooperates with the skimmer plate 45, the collector ring 31 and the head member 37 to provide a substantial chamber 58 within which the impeller rotor 28 is housed operatively. Ready access into the rotor chamber 58 for cleaning and like purposes can be had by removing the various members connected to the head member 37 after the clamps 54 and the bolts 47 have been opened.

Especially efficient separation of the solids from the liquid is effected by the impeller 28 as

a result of the particular construction thereof which directs the liquid and entrained solids horizontally from the distribution chamber 25 in a relatively thin, uniformly distributed layer toward the solids collecting grooves 30. To this end, the impeller 28 is of the shrouded type and comprises a dished top wall 59 radiating from the hub 44. The lower or inner surface of the top wall 59 slopes gently radially outwardly and axially downwardly toward the collector grooves 30. The outer margin of the top wall 59 is formed to curve toward the collector grooves on a relatively large radius and forms a smooth flow-directing lip 60 which has its extremity tapered or feathered to a merger with the upper sides of the collector grooves. Liquid to be clarified is confined between the top wall 59 and a spaced confining or bottom wall 61 which preferably has its inner surface in a horizontal plane coincident with the inner end surface of the stem 52, thereby cooperating with the inner surface of the top wall 59 to afford a gradually diminishing or funnel shape, when considered in radial section, to the centrifugal passages 29 in the impeller. By preference, also, the inner surface of the bottom wall 61 is substantially in a plane with the upper sides of the collector grooves 30 and the terminal edge of the top wall flow-directing lip 60.

The outer peripheral edge of the bottom wall 61 is spaced from the inner diameter of the collector ring 31 to a greater extent than the spacing between the adjacent margin of the bottom wall and the opposing surface of the top wall 59. This affords, in effect, a narrow throat through which the centrifugally driven liquid must pass with a substantially Venturi action and from which it enters the space between the outer edge of the bottom wall 61 and the collector ring 31 and is directed downwardly by the protruding lip 60 into an annular flow-reversal chamber 62 of generous proportions provided in the skimmer plate 45 at the entrance to the skimmer passages 33.

Uniform distribution of the centrifugally driven liquid is assured by a plurality of outwardly divergently spiralling partitions or vanes 63 defining separation for the radially outwardly widening centrifugal flow passages 29. The outer ends of the vanes 63 terminate in the impeller vane extensions 32 which extend in radial planes and extend axially beyond the bottom wall 61, being formed with edge contours complementary to the walls defining the annular flow reversal chamber 62 while their peripheral edges sweep close to the inner diameter of the collector ring 31. In this way all of the centrifugally driven liquid receives equal separating treatment and is positively impelled into the skimmer passages 33. Improved propulsion of the liquid into the skimmer passages is attained by forming those edges of the impeller vane extensions 32 which oppose the entrances to the skimmer passages 33 with beveled flow booster surfaces 64. These booster surfaces 64 also serve to reduce agitation of the impelled clarified liquid as it is driven in reverse direction by the impeller vanes.

To summarize the operation of the centrifuge 10 briefly, liquid to be separated which is supplied continuously through the inlet 20 under low pressure and passes axially through the delivery passage 24 and through the distribution chamber 25 is centrifugally impelled through the centrifugal passages 29 in the impeller where it attains a relatively high centrifugal velocity.

Maximum velocity is reached at the relatively narrow throat defined at the exit from each of the passages 29, the top wall marginal lip 60 directing the solids to be separated toward the collector ring 31 and the clarified liquid into the annular separation and reversal chamber 62. As the solids accumulate in the collector grooves 30 they are progressively expelled through the discharge ports 22 by the pressure of accumulation and the action of the impeller vane extensions 32 acting to urge the accumulated solids onward through the spirally expanding collector grooves to the respective outlets. The clarified liquid, impelled by the vanes 32 passes on through the skimmer passages 33 and the gravity flow passage 34 to the collector chamber 35 and is then drawn off through the discharge port 21. Since the separated solids in the volute groove 30 are subject to controlled back pressure from the valve 23, an ample cake of the solids is maintained at all times in the collector grooves and discharge ports 22 to seal off the liquid from discharge therethrough.

Where a liquid which because of its viscosity tends to carry entrained air therewith is to be handled in the centrifuge, means may be provided for separating the air therefrom as a continuous process coincident with the centrifugal separation of the solids from the liquid.

For this purpose, an air-separating or exhaust structure such as shown in Fig. 5 may be incorporated in the device as a part of the bottom member 50 which has an air duct 65 extending parallel to the delivery passage 24 interiorly of the collector head chamber 35 and communicating at its inner end by way of a take-off or vent port 66 successively with the inner ends of the centrifugal passages 29 in the impeller. By preference, the vent 66 is formed in an integral lip structure 67 which projects above the upper end of the stem 52 into the distribution chamber 25 and with the vent opening in the direction of liquid flow. The lip extremity preferably extends into a clearance groove 67a in the adjacent roof face of the impeller. Any tendency for liquid to escape through the air inlet 66 is minimized since it is drawn past in a direction away from the inlet lip 67. Since the air is the lightest component of the charge in the centrifuge it tends to accumulate adjacent the center of rotation of the impeller and will thus escape through the vent 66 into the air passage 65. From the air passage 65, the air may be drawn off through a lateral passage 68 adjacent the lower end of the bottom member 50 and communicating with an exhaust duct 69 leading to a suitable drain or collecting receptacle to handle such small amount of liquid as may be carried over in the separated air.

Although the centrifuge 10 has been shown as preferably disposed on a vertical axis and with an underfeed and a gravity discharge, it may under certain conditions be found more convenient to use it in a position inverted from that shown or on a horizontal or other angularly disposed axis.

It will, of course, be understood that various details of construction may be varied through a wide range without departing from the principles of this invention, and it is, therefore, not the purpose to limit the patent granted hereon otherwise than necessitated by the scope of the appended claims.

I claim as my invention:

1. In combination in a centrifuge for sep-

arating solids from a liquid and including an enclosing casing having inlet for the solids laden liquid to be treated, an impeller of generally flattened structure having opposite walls with means therebetween defining fluid impelling passages extending outwardly therethrough from a center and with one of the walls extending outwardly beyond the other so that the passages open toward one side of the periphery of the impeller, means for rotation of the impeller, a plurality of radial vanes on said impeller at the passage openings and projecting away from the extending portion of said one wall in the direction of the passage openings, means peripherally surrounding said impeller and presenting a grooved surface for collecting separated solids from the centrifugally treated liquid, means co-operating with said impeller vanes and providing skimmer passage for the separated liquid directed reversely to the centrifugal flow through the impeller, and means for discharge of the separated liquid from the centrifuge.

2. In combination in a centrifuge for separating solids from a liquid and including an enclosing casing having inlet for the solids laden liquid to be treated, an impeller of generally flattened structure having opposite walls with means therebetween defining fluid impelling passages extending outwardly therethrough from a center and with one of the walls extending outwardly beyond the other so that the passages open toward one side of the periphery of the impeller, means for rotation of the impeller, a plurality of radial vanes on said impeller at the passage openings and projecting away from the extending portion of said one wall in the direction of the passage openings, means peripherally surrounding said impeller and presenting a grooved surface for collecting separated solids from the centrifugally treated liquid, means co-operating with said impeller vanes and providing skimmer passage for the separated liquid directed reversely to the centrifugal flow through the impeller, said impeller vanes having booster surfaces thereon for driving the separated liquid through said skimmer passageway, and means for discharge of the separated liquid from the centrifuge.

3. In combination in a centrifuge for separating solids from a liquid and including an enclosing casing having inlet for the solids laden liquid to be treated, an impeller of generally flattened structure having opposite walls with means therebetween defining fluid impelling passages extending outwardly therethrough from a center and with one of the walls extending outwardly beyond the other so that the passages open toward one side of the periphery of the impeller, means for rotation of the impeller, a plurality of radial vanes on said impeller at the passage openings and projecting away from the extending portion of said one wall in the direction of the passage openings, means peripherally surrounding said impeller and presenting a grooved surface for collecting separated solids from the centrifugally treated liquid, means co-operating with said impeller vanes and providing skimmer passage for the separated liquid directed reversely to the centrifugal flow through the impeller, air vent means communicating with the impeller adjacent said center for exhausting air separated from the liquid, and means for discharge of the separated liquid from the centrifuge.

4. In combination in a centrifuge of the char-

acter described including an enclosing casing having inlet for solids laden liquid to be treated, an impeller of substantially flattened structure having a distribution chamber at the center thereof for receiving liquid and entrained solids to be separated, means for effecting rotation of the impeller, the impeller including opposite side walls having means between said walls defining radially extending centrifugal passages therebetween leading from said distribution chamber and opening from the periphery of the impeller, one side wall of the impeller being extended beyond the other side wall of the impeller and providing a curved lip for directing the liquid impelled from said passages in a direction beyond said other side wall of the impeller, means cooperating with said lip for receiving separated solids at the extremity of the lip, means opposing said other side wall of the impeller affording skimmer passageway extending reversely to the impeller passages for receiving the separated liquid, and means for discharge of the separated liquid from the centrifuge.

5. In combination in a centrifuge of the character described including a casing having inlet means for solids laden liquid and outlet means for separated liquid, an impeller adapted to receive at the center thereof from said inlet means liquid and entrained solids to be separated, means for rotation of the impeller, said impeller comprising opposed spaced generally radially extending walls defining impeller passageway therebetween and being convergently related in spaced relation adjacent their periphery whereby the liquid and solids to be separated pass said periphery with substantially Venturi action, and means defining a separation chamber about the periphery of said impeller adapted to collect solids separated from the liquid and having a skimmer passageway for the separated liquid leading from said periphery radially inwardly parallel to the impeller and communicating with said outlet means.

6. In combination in a centrifuge of the character described, a housing including liquid inlet, an impeller in said housing adapted to receive at the center thereof from the inlet liquid and entrained solids to be separated, means for rotation of the impeller, said impeller affording lateral centrifugal passageway for the liquid and solids and including means for impelling the liquid toward and from the periphery of the impeller, said passageway being defined by a wall sloping from the liquid receiving center portion of the impeller to direct the liquid primarily radially outwardly but slightly axially toward one side and terminating in a lip projecting in said axial direction, impeller vanes on the periphery of the impeller extending radially and projecting axially substantially beyond said lip, and means cooperating with said impeller vanes for receiving separated solids and separated liquid.

7. In combination in a centrifuge of the character described, an impeller structure adapted to receive liquid and entrained solids to be separated at the center thereof and affording a generally radially extending passageway including means for impelling the liquid toward and from the periphery of the impeller, means for rotation of the impeller, an annular structure surrounding the impeller peripherally and having volute solids receiving grooves therein enlarging in the direction of rotation of the impeller and having sub-

stantially tangential openings leading from the grooves for discharge of the solids, and vanes at the periphery of the impeller cooperating in close contiguity with said annular structure for impelling the solids on through the grooves.

8. In combination in a centrifuge of the character described including an enclosing housing structure, a centrifugal impeller having opposed wall and dividers between said walls defining relatively flattened passages in the impeller directed toward the periphery thereof and adapted to receive liquid and entrained solids from adjacent the center of the impeller to drive the liquid and solids centrifugally from the periphery of the impeller, means for rotation of the impeller, and a collector ring surrounding the periphery of the impeller, said ring being grooved to receive the solids, and means operative in the rotation of the impeller for impelling the separated liquid radially inwardly away from the collector ring.

9. In combination in a centrifuge of the character described including an enclosing housing structure, a rotary impeller having at one side thereof a wall, means supporting the impeller for rotation, a collector ring peripherally surrounding said impeller, said ring having volute solids-collecting grooves in the impeller opposing surface thereof and opening exteriorly of the ring for discharge of separated solids, said grooves being disposed at an elevation offset relative to the inner side of said impeller wall, an annular directional control lip on the periphery of the impeller having a feathered edge substantially coinciding with that side of the collector grooves which is nearest the inner surface of said wall to direct separated solids into the grooves, and skimmer means for the clarified liquid.

10. In combination in a centrifuge of the character described including an enclosing housing structure, a rotary impeller, means for rotating the impeller, a collector ring peripherally surrounding said impeller, said ring having volute solids-collecting grooves in the impeller opposing surface thereof and opening exteriorly of the ring for discharge of separated solids, a directional control lip on the periphery of the impeller having a feathered edge substantially coinciding with one side of the collector grooves to direct separated solids into the grooves, a confining wall on said impeller having its liquid confining surface substantially in a plane with the extremity of said lip and spaced therefrom to afford substantial clearance for liquid and solids between said edge and the periphery of said wall, and means for receiving the liquid separated from the solids.

11. In combination in a centrifuge of the character described, a drive shaft adapted to be driven rotatably, means for supporting the drive shaft rotatably, a closure member supported by said shaft support, a rotary impeller carried by the shaft adjacent said member and including means for centrifugally impelling liquid laterally therefrom, a collector ring cooperating with said member in encircling relation to the impeller and having solids discharge outlet, a skimmer member cooperating with said collector ring and said impeller, and a second closure member carried by said skimmer member, all of said members being secured together in readily separable fashion and providing a housing enclosing said impeller.

12. In combination in a centrifuge of the character described including an enclosing housing structure, a rotary impeller adapted to receive liquid at the center thereof and affording cen-

trifugal passageway including means for impelling the liquid toward the periphery thereof, means for rotation of the impeller, means at the periphery of the impeller for receiving solids separated from the liquid, a skimmer structure affording reverse liquid passageway for separated liquid, and a head structure supported in rotatably adjustable relation to said skimmer structure and having a collector chamber communicating with said skimmer passageway and affording a discharge port adapted to be directed in preferred angular relation by rotary adjustment of the head structure.

13. In combination in a centrifuge of the character described, a rotary impeller adapted to receive solids carrying liquid and entrained air at the center thereof and affording centrifugal passageway including means for impelling the liquid toward the periphery thereof, means for rotation of the impeller, means at the periphery of the impeller for receiving solids separated from the liquid, a skimmer structure affording reverse liquid passageway for separated liquid, and a structure supported in cooperative relation to said skimmer structure and having a collector chamber for the separated liquid communicating with said skimmer passageway and affording a discharge port, said structure having means for venting air separated from the liquid in the impeller and including a projection extending into communication with the impeller passageway adjacent to the center of the impeller.

14. In a centrifuge for separating solids from a liquid, a first closure member, a collector ring in nested concentric relation with said first closure member and having solids outlet therefrom, a skimmer member supported in nested concentric relation by said collector ring, a second closure member supported in nested concentric relation by said skimmer member, said members cooperating to provide an impeller chamber, a rotary impeller in said chamber and cooperating with said skimmer and second wall members to provide a central liquid distribution chamber, means for rotation of the impeller, a central delivery passage through said second wall member communicating with said distribution chamber, radial centrifugal passages in said impeller for liquid and entrained solids from said distribution chamber directed toward said collector ring, and communicating skimmer passageway and liquid collecting chamber in said skimmer and second closure members.

15. In combination in a centrifuge including an enclosing housing structure having inlet for liquid to be clarified, an impeller having means to receive and drive unclarified liquid at high velocity in a relatively thin layer radially therefrom, means for rotation of the impeller, a solids collecting device surrounding the periphery of the impeller in spaced relation to define therebetween an annular settling chamber within which the

unclarifying liquid is relieved of centrifugal force so that the momentum of the heavier solids will carry them on to the collecting device, and means operating in said chamber and comprising liquid driving elements disposed concentrically relative to the periphery of the impeller to reverse the direction of the clarified liquid and drive it radially inwardly away from the collecting device.

16. In combination in a centrifuge including 10 an enclosing housing structure, an impeller having spaced walls and partitions between said walls defining volute liquid impelling passageways, means for rotation of the impeller, the center of the impeller having a distribution chamber common to all of said passages, means defining an axial passage for delivering unclarified liquid to said distribution chamber, said last-mentioned means including a passage separate from said axial passage and an integral lip structure projecting into said chamber and defining the mouth of said separate passage, said mouth opening close to and toward the mouths of said impeller passageways which are defined by the partitions, whereby air accumulating at the center of the impeller is drawn off through said lip structure as each of said impeller passageways passes said lip structure in the rotation of the impeller thereby.

17. In combination in a centrifuge of the character described for separating solids entrained in a liquid and including an enclosing housing structure, a shrouded relatively flat impeller, means for rotating the impeller, a skimmer cooperatively related to one face of the impeller inwardly of the periphery of the impeller, vanes at the periphery of the impeller, a lip on the periphery of the opposite side of the impeller coactive with the vanes to drive the clarified liquid radially inwardly toward the skimmer, and means radially outwardly of the periphery of said lip cooperative with said vanes and said lip for collecting the centrifugally separated solids.
